Patented Sept. 8, 1908.

Application filed May 1, 1908. Serial No. 430,419. Term of patent 7 years.

To all whom it may concern:

Be it known that I, HENRY J. HERBERT, a citizen of the United States of America, residing at Detroit, in the county of Wayne and State of Michigan, have invented a certain new, original, and ornamental Design for a Handle for Manicuring-Files, Tooth-Brushes, or Similar Toilet Articles, of which the following is a specification, reference being had therein to the accompanying drawings, forming part thereof.

The figure is a plan view of a manicuring file handle, showing my new design.

The salient features of the design reside in the peculiar contour of the handle, and the surfacing of the parts in representation of alligator skin.

I claim:

The ornamental design for a handle for manicuring files, tooth brushes or similar articles, as shown.

HENRY J. HERBERT.
